Bunting & Witt

United States Patent Office.

THOMAS NELSON, OF PHILADELPHIA, PENNSYLVANIA.

Letters Patent No. 96,261, dated October 26, 1869.

IMPROVED TOOL FOR CUTTING TUBES.

The Schedule referred to in these Letters Patent and making part of the same

To all whom it may concern:

Be it known that I, THOMAS NELSON, of Philadelphia, in the county of Philadelphia, and State of Pennsylvania, have invented a new and useful Improvement in Machines for Cutting Iron Pipe, known as "Nelson's Improved Pipe-Cutter;" and I do hereby declare that the following is a full, clear, and exact description of the construction and operation of the same, reference being had to the annexed drawings.

This machine consists of an iron frame, in which a knife is moved by means of a screw. It is of sufficient size to permit its revolving around the pipe while cutting it, the knife being pressed down by the screw during the cutting, as occasion requires.

The body or frame consists of three pieces, and is made of wrought-iron or any other suitable material. These pieces consist of a frame or back, A, and two side pieces, B B', as shown in Figures 1 and 2 of the drawing.

At the top of the machine, an opening is made, for the admission of the screw C, which operates the knife.

The side pieces are removable, for the purpose of taking out the knife D, when desirable, or while not in use.

At the base of the machine are two oval jaw-facings, E E', placed side by side, and held in place by the side pieces B B'.

I will now proceed to describe the method of operating my machine.

The pipe to be cut is placed in a vise, or other suitable machine, for holding it firmly, and the machine is placed upon it, so that the pipe passes into the opening O, resting upon the jaw-facings E E'. The knife being screwed tightly down, and pressing upon the pipe, the upper part of the machine is then grasped and revolved, the operator screwing the knife gradually down, until the pipe is cut through.

Having thus described my invention,

What I claim, and desire to secure by Letters Patent, is—

Constructing a pipe-cutting machine of the several pieces A B B', the screw C, knife D, and jaw-facings E E', in the manner set forth.

THOS. NELSON.
